UNITED STATES PATENT OFFICE.

WILLIAM H. ROBBINS, JOHN J. BYE, AND ALBERT E. JONES, OF ELLWOOD CITY, PENNSYLVANIA.

MILL FOR ROLLING SEAMLESS TUBES.

SPECIFICATION forming part of Letters Patent No. 692,478, dated February 4, 1902.

Application filed May 21, 1901. Serial No. 61,236. (No model.)

To all whom it may concern:

Be it known that we, WILLIAM H. ROBBINS, JOHN J. BYE, and ALBERT E. JONES, citizens of the United States, residing at Ellwood 5 City, in the county of Lawrence and State of Pennsylvania, have invented new and useful Improvements in Mills for Rolling Seamless Tubes, of which the following is a specification.

Our invention relates to mills for rolling seamless tubes, and more particularly to the means employed for securing the swages or tube-shaping dies on the rolls. It contemplates fastening the swages or dies on the rolls without the employment of keys or wedges, which are objectionable because of their liability to work loose, and this in such manner that while there is no liability of the swages or dies becoming loose in practice 15 they may be expeditiously removed and replaced with other dies when desired.

Other advantageous features of the invention will be fully understood from the following description and claims when taken in conjunction with the accompanying drawings, 20 in which—

Figure 1 is a front elevation of a rolling-mill embodying our invention with one of the housings in section. Fig. 2 is a transverse section taken on the line 2 2 of Fig. 1. Fig. 3 is a perspective view illustrating a portion of one of the rolls of the mill. Fig. 4 is a top plan view of the lower roll with the swage or die fastened thereon, and Fig. 5 is 35 a perspective view of one of the dies or swages removed from its roll.

In the said drawings similar letters of reference designate corresponding parts in all of the several views, referring to which—

40 A A are the housings of a rolling-mill, B B are rolls journaled in suitable bearings in the housings, and C C are swages or dies provided with grooves a for giving shape to seamless tubes. The rolls B are respectively 45 provided with two enlargements D E, arranged about the distance illustrated apart, so as to receive between them the swages or shaping-dies, and said rolls are also provided at points intermediate of the enlargements 50 D E with threaded sockets b, disposed as best shown in Fig. 2 for a purpose presently

pointed out. The enlargements D are provided in their inner faces with semicircular grooves c, while the enlargements E are provided at their inner sides with inclined faces 55 d, disposed obliquely with respect to the longitudinal centers of the rolls, as best shown in Figs. 1 and 4. The swages or dies, which are semicircular in shape, are provided with square ends to meet the square faces of the 60 enlargements D and semicircular lugs e on said ends to enter the grooves c of the enlargements, and said swages or dies are also provided with ends f, inclined in conformity to the inclined faces d of the enlargements E, 65 whereby it will be seen that they may be wedged between the enlargements D E.

F F are bolts arranged in the threaded sockets b of the rolls B and provided with heads g, having threaded apertures h, and G 70 G are bolts bearing in the said apertures h of the bolts F and arranged to engage the inner reduced ends of the swages or dies C after the manner illustrated in Figs. 1 and 2.

In the practice of our invention it will be 75 observed that when the swages or dies are interposed between the enlargements D E of the rolls B, with their semicircular lugs e arranged in the complementary grooves c of the enlargements D and their inclined ends f 80 bearing against the inclined faces d of the enlargements E, they will be securely wedged between and held to the enlargements and the rolls B and in consequence will not be liable to become loose in practice. It will 85 also be observed that the bolts G serve as stops for the swages or dies and are also adapted to be used to advantage in starting the swages or dies when it is desired to remove the same to give place to other swages 90 or dies.

The grooves a of the swages or dies have a radius of from four and one-half to eight inches and extend throughout the length of the swages or dies, as shown.

It will be appreciated from the foregoing that by virtue of the inclined ends f of the swages or dies and the complementary inclined faces d of the enlargements E the swages or dies are secured between the enlargements D E in a wedge-like manner, and in consequence the necessity of employing 95 100

keys, wedges, or other auxiliary appurte-
nances for fastening the swages or dies is ob-
viated, which is a highly important advan-
tage.

5 We have entered into a detail description
of the construction and relative arrangement
of parts embraced in the present and pre-
ferred embodiment of our invention in order
to impart a full, clear, and exact understand-
ing of the same. We do not desire, however,
to be understood as confining ourselves to
such specific construction and arrangement
of parts, as such changes or modifications
may be made in practice as fairly fall within
15 the scope of our claims.

Having described our invention, what we
claim, and desire to secure by Letters Patent,
is—

1. The combination with a roll having an
enlargement provided in its inner side with
20 a groove, and another enlargement provided
with an inclined inner face; of a swage or
die adapted to be interposed between the en-
largements of the roll, and having a lug or
25 tongue at one end to enter the groove in one
enlargement, and also having its opposite end
inclined in conformity to the inclined inner
face of the other enlargement.

2. The combination with a roll having an
enlargement provided with an inclined inner
30 face, and also having another enlarge-
ment; and a projection interposed between
the enlargements; of a swage or die adapted
to be interposed between the enlargements of

the roll, and having one of its ends inclined in 35
conformity to the inclined inner face of one
enlargement, coacting means on the other en-
largement and the swage, whereby the latter
is held to the former, and an adjustable de-
vice bearing in the projection of the roll and 40
adapted to engage the inner edge of the
swage.

3. The combination with a roll having an
enlargement provided in its inner side with
45 a groove, and another enlargement provided
with an inclined inner face, and also having
a threaded socket arranged intermediate of
the enlargements; of a swage or die adapted
to be interposed between the enlargements of
50 the roll and having a lug or tongue at one end
to enter the groove in one enlargement, and
its opposite end inclined in conformity to the
inclined inner face of the other enlargement,
a bolt arranged in the threaded socket of the
roll and having a head provided with a thread-
55 ed aperture, and a bolt bearing in said aper-
ture and arranged to engage the inner end of
the swage.

In testimony whereof we have hereunto set
our hands in presence of two subscribing wit-
nesses.

WILLIAM H. ROBBINS.
